FRANCIS A. DEVEREAUX, OF ANOKA, MINNESOTA, ASSIGNOR TO BERTRAND P. MURPHY,
OF ANOKA, MINNESOTA

WRENCH

63

Application filed August 10, 1929. Serial No. 384,961.

It is the object of this invention to provide a novel and improved wrench of cheap and simple construction having co-operating, fixed and movable jaws at one end thereof, 5 which are adjustable to and from each other to receive nuts and bolts of various sizes, which wrench can be readily held in one hand of an operator for use, and which jaws can be adjusted relative to each other without re- 10 moving the hand from the wrench.

To this end, the invention consists in the novel parts and novel combinations of parts, hereinafter defined in the claims and described in the following specification, made 15 in connection with the accompanying drawings, wherein like reference characters refer to the same or similar parts throughout the various views, and, in which,

Fig. 1 is a side view of the wrench; 20 Fig. 2 is an edge view of the wrench; Fig. 3 is a longitudinal section taken on the line 3-3 of Fig. 1, as indicated by the arrows;

Fig. 4 is a section taken on the line 4-4 25 of Fig. 1, and

Fig. 5 is a section taken on the line 5-5 of Fig. 1.

Referring to the drawings, the wrench consists essentially of five parts, a stationary 30 member 6, a movable member 7, a screw 8, a nut 9 and a pin 10. The stationary member 6 may be considered to be divided up into a handle shank 6a, a narrow and widened bearing portion 6b joining the forward end 35 of the handle shank 6a and fixed jaw 6c joining the forward and left end of the bearing portion 6b, as viewed in Fig. 1 of the drawings. The shank 6a has a circular opening 6d at its rear end which serves to lighten 40 the wrench and provide a convenient means for permitting the wrench to be hung up on a hook or the like, and forwardly from the opening 6d a long slot 6e is preferably provided in the shank 6a to also lighten the 45 wrench and to aid in the ease of the manufacture of the wrench. Forwardly from the slot 6e, a substantially rectangular-shaped opening 6f is provided in the shank 6a and the nut 9 is situated within this opening, the 50 nut being provided with a knurled surface

to permit the same being readily turned by the thumb or finger of the operator. The opening 6f joins a forwardly extending slot 6g which runs from the opening 6f forwardly into the bearing portion 6b of the stationary member and is widened at its forward end. The screw 8 fits within the opening 6g and runs through the nut 9 and is provided at its forward end with a widened and flattened head carrying the cross pin 10, the said widened head fitting within the widened forward portion of the slot 6g. To permit longitudinal movement of the screw 8 relative to the shank 6a, the longitudinal opening 6h is provided in the shank 6a and in order that this opening may be readily bored, the openings 6i are provided in the rear end of the shank. The axial center line of the screw 8 is preferably coincident with the longitudinal center line of the shank 6a and extending diagonally relative to the said axial center line of the screw 8 and at what may be considered an acute angle thereto, are ribs 6j formed on the bearing portion 6b and projecting therefrom. The ribs 6j may, roughly speaking, accordingly, be considered as extending diagonally relative to the shank and at an acute angle thereto. As was stated, the bearing portion 6b is quite narrow relative to the shank 6a and is also quite narrow 55 relative to the jaw 6c and, accordingly, shoulders 6k and 6l are formed on the two sides of the member 6 at the point of juncture between the shank 6a and the bearing portion 6b and the jaw 6c and the bearing portion 6b, respectively. The shoulders 6k and 6l extend parallel to the ribs 6j for a purpose presently to appear. The forward right hand edge 6m of the bearing portion 6b, as seen in Fig. 1, also extends parallel to the ribs 6j, while the active edge of the jaw 6c extends at right angles to the ribs 6j.

The movable member 7 consists of a movable jaw 7a adapted to co-operate with the fixed jaw 6c and extending parallel thereto, 95 and the movable member also included a wide bearing portion 7b joining the movable jaw 7a and formed in two parts to straddle and bear against the bearing portion 6b of the fixed member 6. Diagonal grooves 7c are 100

provided in the bearing portion 7b of the movable member to receive the ribs 6j and the rear edge 7d of the bearing portion 6b extends parallel to the ribs 6j and bears against the shoulders 6k. The forward left hand edge 7e of the bearing portion 7d also extends parallel to the ribs 6j and is adapted to bear against the shoulders 6l at certain times during the movement of the movable member 5 across the stationary member. The edge 7f 10 between the two straddling sections of the bearing portion 7b of the movable member also extends parallel to the ribs 6j and is adapted to bear against the forward right hand edge 6m of the bearing portion 6b of the stationary member, as best shown in Fig. 1. It will thus be seen that practically all 15 surfaces of the bearing portion 7b of the movable member either bear directly against or are adapted to bear directly against portions of the bearing portion 6b of the stationary member.

To receive the ends of the cross pin 10, diagonal guideway slots 7g are cut in the bearing portion 7b of the movable member 25. The slots 7g are set at an obtuse angle relative to the longitudinal axial center of the screw 8 and the handle shank 6a, and preferably this angle will equal the acute angle formed between the ribs 6j and the axial longitudinal center line of the screw 8 30 and the shank 6a plus 90 degrees. Roughly speaking, the guideway slots 6g extend diagonally relative to the handle shank 6a and in a direction generally opposite to the direction of extension of the ribs 6j. In the form of the invention illustrated, the acute angle formed between the ribs 6j and the axial center line of the screw 8 and shank 6a is 35 22½ degrees, while the obtuse angle formed between slots 7g and the axial center line of the screw 8 and shank 6a is 112½ degrees. It is possible, of course, to change these angles as desired.

In use, the wrench will be grasped with one hand of the operator about the handle shank 6a. The operator can then adjust the spacing between the jaws 6c and 7a by merely turning the nut 9 with the thumb of the hand grasping the wrench. As the nut 9 is turned, the screw 8 will move longitudinally of the shank, thereby moving the pin 10 in the slots 7g and causing the movable member 7 to slide diagonally of the bearing portion 6b of stationary member 6 along a line parallel to the ribs 6g. Due to the fact that the obtuse angle formed between the slots 7g and the longitudinal center line of the screw 8 and shank 6a equals the acute angle formed between the ribs 6j and the longitudinal center line of the screw 8 and shank 6a, plus 90 degrees, the movable member 7 may 60 be moved with equal facility in either direction to widen the spacing between the jaws 6c and 7a or to narrow the spacing therebe-

tween. The wrench can accordingly be adjusted to fit nuts and bolts of various sizes by use of only one hand of the operator, i. e., the hand grasping the wrench. As practically all portions of the movable member 7 bear 70 against portions on the fixed member 6, it will be seen that when the jaws are adjusted, a very strong wrench will be formed and the movable jaw 7a will not yield in any direction as the wrench is used on a nut or bolt. 75 The jaws can, accordingly, be adjusted relative to each other with fine accuracy and will hold their position without movement when so adjusted.

The wrench has been amply demonstrated 80 in actual practice, and has been found to be very successful for the purposes intended. It is, of course, within the scope of the present invention, to reverse certain of the parts on the stationary and movable members.

It will, of course, be understood that various changes may be made in the form, details, arrangement and proportions of the various parts without departing from the scope of the present invention.

What is claimed is:—

1. A wrench comprising a stationary member having a handle shank, a bearing portion at one end of said shank, and a fixed jaw secured to said bearing portion, a movable member having a movable jaw and a bearing portion fitting against the bearing portion of said stationary member and movable thereacross, means for confining the movement of said movable member across the bearing portion of said stationary member in a direction extending diagonally relative to said shank, said movable member having a guideway therein extending diagonally relative to said shank and in an opposite direction than the direction of movement of said movable member across the bearing portion of said stationary member, a member having a portion fitting within said guideway and means for moving said last mentioned member substantially longitudinally of said shank to slide said movable member on said stationary member and vary the spacing between said two jaws.

2. A wrench comprising a stationary member having a handle shank, a bearing portion at one end of said shank and a fixed jaw secured to said bearing portion, a movable member having a movable jaw and a bearing portion fitting against the bearing portion of said stationary member and movable thereacross, a rib on one of said bearing portions and extending diagonally relative to said shank, the other of said bearing portions having a co-operating groove within which said rib is received, said movable member having a guideway therein extending diagonally relative to said shank and in a direction generally opposite the direction of extension of said rib relative to said shank,

a member having a portion fitting within said guideway, and means for moving said last mentioned member substantially longitudinally of said shank to slide said movable member on said fixed member and vary the spacing between said two jaws.

3. A wrench comprising a stationary member having a handle shank and a fixed jaw secured to one end of the same, a movable member having a movable jaw and mounted for sliding movement across said stationary member, means for confining the movement of said movable member across the stationary member in a direction extending at an acute angle relative to the length of said shank, said movable member having a guideway therein extending at an obtuse angle relative to the length of said shank, said obtuse angle equalling said acute angle plus a right angle, a member having a portion fitting within said guideway and means for moving said last mentioned member substantially longitudinally of said shank to slide said movable member on said stationary member to vary the spacing between said two jaws.

4. A wrench comprising a stationary member having a handle shank, a bearing portion at one end of said shank and a fixed jaw fixed to said bearing portion, a movable member having a movable jaw and a bearing portion straddling the bearing portion of said stationary member, co-operating means on said two bearing portions confining the movement of said movable member on said stationary member in a diagonal direction relative to the length of said shank, a slot diagonal in the bearing portion of said movable member extending generally opposite to the direction of movement of the movable member, a pin working within said slot, a screw secured to said pin and extending longitudinally of said shank and a thumb nut mounted in said shank and through which said screw works.

In testimony whereof I affix my signature.

FRANCIS A. DEVEREAUX.
